UNITED STATES PATENT OFFICE.

CARLETON ELLIS, OF MONTCLAIR, NEW JERSEY, ASSIGNOR TO NEW JERSEY TESTING LABORATORIES, A CORPORATION OF NEW JERSEY.

INSTITUTE FOR MISSING XR

FLAME-PROOF INSULATION.

1,246,809.

Specification of Letters Patent. Patented Nov. 13, 1917.

No Drawing. Application filed July 26, 1915, Serial No. 41,924. Renewed September 14, 1917. Serial No. 191,502.

To all whom it may concern:

Be it known that I, CARLETON ELLIS, a citizen of the United States, and a resident of Montclair, in the county of Essex and State of New Jersey, have invented certain new and useful Improvements in Flame-Proof Insulations, of which the following is a specification.

This invention relates to what may be termed "flame proof" insulation and relates especially to a composition comprising chlorinated petroleum material and the like.

Chlorinated bodies or mixtures suitable for the purpose may be obtained by treating with chlorin various petroleum oils such as mineral and asphaltic oils of a more or less unsaturated character. The heavy oils of Texas and particularly the Mexican oils are well suited for this purpose. Other oils preferably containing some asphaltic material may be used. The residues from cracking stills also afford products which may be used for the present purpose. By treating these various oils with chlorin using iodin or similar carrier to aid in the chlorination a considerable amount of chlorin may be introduced either by addition or substitution and chlorinated products are obtained which do not ignite readily when exposed to flame and which possess the characteristics termed flame proof. This means that the composition does not readily transmit flame, so that a wire coated with the material if ignited under test conditions at one point does not permit the flame to travel along the insulation for an indefinite distance.

A suitable composition for the present purpose may be obtained by chlorinating heavy Mexican oils at a temperature of 80-100° C., using iodin as a carrier. The excess of acid and chlorin may be removed by heating or washing with alkaline solutions. The composition is applied to the conducting material such as a copper wire and this application may be made directly to the metal or to a coating of some insulating material such as rubber already surrounding the metal. The flame proof coating may be formed as an annular or concentric layer surrounding the wire and concentric insulating material. In some cases an inner layer of rubber may be used and over this a fabric of cotton material or the like may be woven and this fabric immersed in

the chlorinated composition to form a coating which has the flame proof qualities required.

The chlorinated petroleum oil may be admixed with other bodies such as waxes or chlorinated waxes, asphaltic oils and the like which are compatible with the adjacent insulation in the case rubber and the like is used. The flame proof composition should be compatible with the rubber when the latter is used and not cause the rubber to soften, crack or decay prematurely. Under these circumstances it may be necessary to have all volatile oils and rubber softening material removed from the petroleum product as this material frequently contains substances which tend to cause decay of rubber. In this manner there is obtained a compatible coating composition which effectively flame proofs the exterior, and at the same time is without deleterious action on the interior layers.

Chlorinated fish oil dissolved in asphaltic oil or tar may be employed in conjunction with the foregoing. Other chlorinated bodies such as highly chlorinated naphthalene may also be incorporated with the above mentioned bodies.

What I claim is:—

1. An insulating composition comprising a chlorinated product of heavy petroleum incorporated with other insulating material.

2. An insulating composition comprising chlorinated petroleum oil admixed with combustible organic plastic insulating material in proportion to render the composition substantially flame proof.

3. An insulating composition comprising a product of a plastic nature containing chlorinated petroleum admixed with combustible material of a plastic nature, the proportion of the former being sufficient to reduce the inflammability to an extent such that if ignited at any given spot the flame does not travel along the surface of the material for any substantial distance but is quickly extinguished by the presence of the chlorinated material.

4. An insulating composition comprising a chlorinated mineral oil product admixed with other insulating material, the proportion of the former being sufficient to reduce the inflammability to an extent such that if ignited at any given spot the flame does not

- readily travel along the surface of the composition for any substantial distance but is duly extinguished by the chlorinated component.
5. An insulating composition comprising a chlorinated oil product admixed with other insulating material, the proportion of the former being sufficient to reduce the inflammability to an extent such that if ignited at any given spot the flame does not readily travel along the surface of the composition for any substantial distance but is extinguished by the presence of the chlorinated component.
- 10 6. An insulating composition comprising a chlorinated product of petroleum incorporated with other insulating material.
7. An insulating composition comprising a mixture containing a substantially fixed chlorinated oil admixed with combustible organic plastic insulating material in proportion to render the composition substantially flame proof.
- 20 8. An insulating composition comprising a product of a plastic nature containing chlorinated asphaltic oil material admixed with combustible insulating material of a
- plastic nature, the proportion of the former being sufficient to reduce the inflammability to an extent that if ignited at any given spot the flame does not travel along the surface of the material for any substantial distance but is quickly extinguished by the presence of the chlorinated material.
- 30 9. An insulating composition comprising combustible insulating material incorporated with the non-volatile chlorinated derivatives of asphaltic material; the proportion of the latter being sufficient to reduce the inflammability to an extent such that if ignited at any given spot the flame does not travel along the surface of the composition for any substantial distance but is duly extinguished by the presence of the chlorinated constituent.
- 35 10. An insulating composition adapted for use in the coating of wire comprising plastic insulating material incorporated with chlorinated organic material comprising chlorinated asphaltic oil of a non-inflammable character; sufficient of the latter being present to render the composition substantially flame proof.
